UNITED STATES PATENT OFFICE.

SIEGMUND LOEWE, OF BERLIN, FRIEDENAU, GERMANY, ASSIGNOR TO RADIO CORPORATION OF AMERICA, A CORPORATION OF DELAWARE.

RADIO RECEIVING CIRCUIT.

Application filed November 12, 1926, Serial No. 147,971, and in Germany October 21, 1925.

This invention relates to a receiver arrangement and more particularly to a receiving circuit using an intermediate-frequency amplifier.

5 A number of receiving arrangements work with an intermediate or beat frequency which is produced by a local oscillator whose frequency differs from the incoming wave by the intermediate or beat frequency. In receiver 10 apparatus of the said sort, it is customary according to former practice, to use intermediate-frequency amplifiers comprising three or four amplifier stages which are inter- 15 coupled by tuned systems. For example, for superheterodyne and ultradyne circuit arrangements, it is customary to use intermediate-frequency amplifiers coupled by tuned 20 transformers or induction coils. Tuning when such intermediate-frequency amplifiers were used was an absolute necessity for two 25 reasons (1) because sensitive amplifiers for higher frequencies could be built with only tuned coupling means, and (2) because sharp selection of the intermediate-frequency 30 amplifier has been the most decisive point in determining the selectivity of the entire receiving apparatus. Hence, it seems obvious that resistance-coupled amplifiers fundamentally 35 appeared unsuited for this purpose.

An object of this invention consists in the creation of a highly selective intermediate amplifier comprising the use of aperiodically inter-coupled amplifier stages.

Another object of this invention is to provide an arrangement wherein the amplification of any chosen intermediate frequency may be easily and efficiently accomplished.

A further object of this invention is to provide a receiving circuit wherein a single amplifier is used to simultaneously amplify currents of differing frequencies.

It will be understood that every aperiodic radio frequency amplifier can be changed into a selective amplifier by tuning the input circuit of the aperiodic amplifier to the wave to be amplified. By the combination of an aperiodic amplifier with a tuned circuit, there is obtained a selectively acting amplifier arrangement which not only fully measures up 50 to the above demands relative to the intermediate-frequency amplifier but which even exceeds these demands on two counts. The combination as before suggested, renders it possible to readily alter the frequency to 55 which the intermediate-frequency amplifier

has been tuned. In the case of amplifiers coupled by tuned inductance coils, or oscillation circuits, upon altering the intermediate frequency, as many resettings in tuning are required as there are amplifier stages. In 60 the case of the amplifier suggested here all that is necessary is to change the tuning of the series selection circuit.

The operation and construction of such an amplifier is simpler, and its utility is substantially greater than that of amplifiers heretofore used.

But a further advantage and merit, is that one and the same amplifier can without any trouble be employed as an intermediate-frequency amplifier and as a low frequency amplifier. It is even feasible to use the same amplifier for radio frequency, intermediate, and low frequency amplification in one and the same receiver circuit arrangement.

In the accompanying drawings Figure 1 is a wiring diagram showing an arrangement wherein a single resistance coupled amplifier is used to produce amplification of both intermediate and audio frequency currents; and

Figure 2 shows the connections whereby a single amplifier may be used to amplify radio, intermediate and audio frequency currents.

Figure 1, on the left-hand side, shows the customary receiving arrangement comprising the use of intermediate frequency. 1 is the aerial, 2 a grid circuit tuned to the incoming wave, 3, 4, 5, 6, 7, 8 are amplifier tubes. The plate circuit of the tube 3, by way of the neutralized coil 9, is brought to the positive terminal 10 of the joint plate battery. All of the filaments of the tubes are connected in parallel between the joint negative pole 11 and the positive pole 12. The grid circuit 2 is branched off from a potentiometer 30. The radio-frequency current amplified by the first-stage tube 3 is fed to the grid circuit 13 of tube 4 which acts as a combining tube and which is supplied with potential from the regeneratively coupled tube 5 which is usually 100 tuned to half the frequency of the incoming wave, being slightly detuned with reference to it in such a manner that a substantially slower intermediate frequency is set up in circuits 15, 16 which is modulated in the same manner as the incoming waves. Circuit 16 according to the invention constitutes the input circuit of an aperiodic radio frequency amplifier arrangement comprising tubes 6, 7, 8 which, by the series-connection of this cir- 110

cuit 16 is given a very sharp selectivity. In case it is intended to alter the intermediate frequency, all that is necessary is to change the tuning of circuit 16 to the desired intermediate frequency in order to thereby readjust the entire intermediate-frequency amplifier to the modified intermediate frequency.

In Figure 1 the intermediate-frequency amplifier 6, 7, 8 is coupled by high-ohmic resistances 17, 18 through capacities 19, 20, the grids having also leaks consisting of high-ohmic resistances 21, 22. In the output circuit is connected a telephone receiver, 23 shunted by a bypass condenser 23' and also a condenser shunted transformer 24 which feeds the grid of tube 6 again with the low frequency component resulting from the rectification effect of the radio frequency tube. The resistance-coupled amplifier is in a position, without its function as intermediate-frequency amplifier being thereby impaired, to produce an efficient low frequency amplification. Now, if the amplifier 6, 7, 8 is to be used at the same time for radio frequency amplification, first-stage tube 3 together with its circuit appurtenances is omitted. This is shown in Fig. 2. The grid circuit 2 (Fig. 2) is then inserted at the point of the grid lead of tube 6 marked by a cross (see Fig. 1) and so causes the antenna to transfer energy to this circuit. In the plate circuit of tube 8 is further connected, at the place marked by a cross (see Fig. 1), a coil 22 which is caused to act inductively upon the coil of the grid circuit 13 (see Fig. 1). What remains of the circuit arrangement are five tubes only, i. e., the modulator tube 4, the generator tube 5 and the three resistance-coupled amplifier tubes 6, 7, 8, which act at the same time as low frequency intermediate-frequency, and radio frequency amplifiers.

Figure 2 shows completely this modification where the sensitivity attained by virtue of this arrangement is extremely high. The operation of the system shown in Fig. 2 is, briefly, as follows. Circuit 2 is tuned to the desired incoming signal and the resulting variations in potential across it are applied

across the grid and filament of tube 6. The incoming radio frequency wave is then amplified by tubes 6, 7 and 8. From tube 8, the amplified received radio frequency oscillations are fed into combining tube 4 by means of coil 22 and circuit 13 and are "mixed" with locally produced oscillations from tube 5. Circuit 15 feeds into 16 the resulting intermediate frequency energy which in turn is fed to the input side of tube 6. This intermediate frequency energy is then amplified and detected by tubes 6, 7 and 8. The audio frequency component of the energy appearing in the plate circuit of tube 8 will then be reflexed into tube 6 by means of transformer 24, amplified by tubes 6, 7 and 8 and then be of a sufficient amplitude to actuate receivers 23.

In this manner the resistance coupled amplifier system 6, 7 and 8 is utilized to effect radio, intermediate and audio frequency amplifications.

Having thus described my invention, what I claim is:

In radio receiving apparatus, a tunable input circuit; a radio frequency amplifier comprising a vacuum tube having a control electrode, a cathode and an anode; a source of potential for energizing the cathode of said tube; a resistance across said source of potential; connections from said tunable input circuit to said control electrode and resistance; means for heterodyning the output of said amplifier; means for amplifying the intermediate frequency caused by said heterodyning, said last mentioned means comprising a plurality of resistance coupled amplifier tubes, a plurality of which have grid leak resistances connected across their control electrodes and filaments; and means for reflexing the output of the last tube of said intermediate frequency amplifier into the first tube of said intermediate frequency amplifier, said intermediate frequency amplifier being thereby utilized for amplifying and detecting intermediate frequency oscillations and for amplifying the resulting audio frequency oscillations.

SIEGMUND LOEWE.

CERTIFICATE OF CORRECTION.

Patent No. 1,686,621.

Granted October 9, 1928, to

SIEGMUND LOEWE.

It is hereby certified that error appears in the printed specification of the above numbered patent requiring correction as follows: Page 1, line 25, after the word "coil" for the numeral "22" read "32"; and that the said Letters Patent should be read with this correction therein that the same may conform to the record of the case in the Patent Office.

Signed and sealed this 22nd day of January, A. D. 1929.

(Seal)

M. J. Moore,
Acting Commissioner of Patents.
